UNITED STATES PATENT OFFICE.

FREDERIC AUMONIER, OF LONDON, ENGLAND.

DESIGN FOR WALL-PAPER.

SPECIFICATION forming part of Design No. 22,764, dated August 29, 1893.

Application filed August 1, 1893. Serial No. 482,134. Term of patent 3½ years. Patented in England March 3, 1893, No. 208,529.

To all whom it may concern:

Be it known that I, FREDERIC AUMONIER, trading as WM. WOOLLAMS & Co., a subject of the Queen of Great Britain, and a resident 5 of 110 High Street, near Manchester Square, London, England, have invented a new and useful Design for Wall-Paper, (patented in Great Britain on the 3d day of March, 1893, No. 208,529,) of which the following is a specification.

This design of wall paper as illustrated by the accompanying drawing consists of narrow ribbon like leaves and broad jagged edged

leaves ascending in wavy formation peony like flowers being arranged on each side alternately looking upwardly and downwardly. 15

I claim

The design for wall paper substantially as herein shown and described.

FREDERIC AUMONIER.
